UNITED STATES PATENT OFFICE.

HIRAM D. WOOD, OF ALEXANDRIA, MISSOURI.

DUMP END GATE.

Application filed January 20, 1922. Serial No. 530,586.

To all whom it may concern:

Be it known that I, HIRAM D. Wood, a citizen of the United States, residing at Alexandria, in the county of Clark and State of Missouri, have invented a new and useful Dump End Gate, of which the following is a specification.

This invention relates to end-gates for wagon bodies or the like, and more particularly to end-gates of the scoop type.

The primary object of the invention is to provide an end-gate of the combined scoop and dump type, novel means being provided for securing the gate in its open and closed positions.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:—

Figure 1 is a side elevational view of an end-gate constructed in accordance with the present invention, a portion of a wagon body being shown.

Figure 2 is a plan view of the same.

Figure 3 is a sectional view taken on line 3—3 of Figure 2.

Figure 4 is a rear elevational view of the gate in a closed position.

Figure 5 is a side elevational view showing the gate in an open position.

Referring to the drawings in detail, the wagon body to which the gate is attached, is indicated by the reference character 5 and is formed with end boards 6 secured to the wagon body and disposed in spaced relation with the side boards thereof.

The end-gate embodies side plates 7 which have portions thereof extending at right angles to form supports 8 for the end board 9 of the end-gate. Securing members 10 secure the end board 9 to the right angled portions 8 of these plates, the securing members 10 also passing through the bars 11 which connect the right angled portion 8 at points adjacent to the upper and lower ends thereof.

As shown, the end wall 9 terminates at a point in spaced relation at the lower ends of the plates 7 to provide an opening for al-

lowing material to be dumped under the wagon body through the opening. A closure indicated at 12 is hingedly connected to the bar 11 as by means of the hinges 13, 60 whereby the opening may be closed to prevent material passing from the wagon body to which the end-gate is supplied.

Secured to the closure 12 is a bar 14 on which are mounted keepers 15, the keepers being secured to the bar 14 as by means of securing bolts 16, which are shown as passing through registering openings in the body portions of the keepers, and bar 14.

These keepers 15 have their free ends extended beyond the outer surfaces of the side plates 7, where the same are formed with notched portions 17, designed to accommodate the crank arms 18 that are secured to the side plates 7 as by means of the brackets 75 19. Thus it will be seen that when the closure is in its closing position, the crank arms 18 may be moved to engage the keepers 15 and secure the closure against movement.

The end-gate supporting means include bars 20 which are pivotally secured to the plate 7 as at 7' to permit the same to pivot with respect thereto, the bars 20 being however positioned on the inner surface of the plate 7 and formed with elongated openings 85 8' to accommodate the pins 7. At the outer end of each of the bars 20 is a relatively short pivoted bar 21 which has pivotal connection with the bar 20 associated therewith, and as shown, each of these bars 21 is 90 formed with an opening to accommodate one end of a rod 22.

The free end of each of the rods 22 is formed with a curved portion 23 operating through a keeper 24 associated therewith, the keepers 24 being however secured to the outer surfaces of the plate 7, in any suitable manner. Thus it will be seen that the curved portions 23 of the rods 22 may engage with the keepers 24 to support the end-gate proper in a position as indicated by Figure 5 of the drawings, whereupon the end-gate may be used by a person scooping the material from the wagon body.

Pivotedly supported between the bars 20 and 21 are the hook members 25, which also assist in supporting the end-gate in a position as shown by Figure 5 of the drawings, the hook members 25 being constructed to contact with one edge of the end boards 6. 105 Supporting brackets 26 are also secured to the side plates 7 and accommodate portions

of the rods 22 to insure against the rods pivoting when the gate is in a horizontal position.

Having thus described the invention, what is claimed as new is:—

An endgate for wagon bodies comprising end boards secured to the wagon body, a gate section having side plates adapted to embrace portions of the end boards when 10 the gate is moved to its closed position, keepers secured to the side plates at points in spaced relation with the ends thereof, a supporting means comprising pivoted bars having connection with the side plates, hook 15 members pivotally connected to the bars at

the upper ends thereof, bars having pivotal connection with the hook members, bracket members secured to the plates, rods having connection with the last mentioned bars and having curved portions for engagement with 20 the keepers, and said rods and bars adapted to secure the endgate in its open and closed position.

In testimony that I claim the foregoing as my own, I have hereto affixed my signature in the presence of two witnesses. 25

HIRAM D. WOOD.
